UNITED STATES PATENT OFFICE.

PHILIP JOHNSTON, OF MERRICK, OKLAHOMA.

COMB-CLEANER.

1,245,463.

Specification of Letters Patent.

Patented Nov. 6, 1917.

Application filed April 13, 1917. Serial No. 161,840.

To all whom it may concern:

Be it known that I, PHILIP JOHNSTON, a citizen of the United States, residing at Merrick, in the county of Lincoln and State of Oklahoma, have invented certain new and useful Improvements in Comb-Cleaners, of which the following is a specification.

My invention relates to improvements in combs, and it consists in the constructions, 10 combinations, and arrangements herein described and claimed.

An object of my invention is to provide a comb including a sheath or casing adapted to be fitted and clamped over the spine 15 of the comb, said sheath including grids adapted to enter the spaces between the comb teeth, so that after continued use of the comb, the sheath may be loosened and moved outwardly whereupon the grids will 20 remove all accumulations from the teeth of the comb.

Another object of my invention is to provide a sheath for the purpose specified, including hinged side members having a clasp, 25 said side members being adapted to engage the sides of the comb spine and the clasp being adapted to secure the sheath in position upon the comb.

Other objects and advantages will appear 30 from the following specification, reference being had to the accompanying drawing, in which:

Figure 1 is a side elevation of the comb illustrating the application of my invention,

Fig. 2 is a side elevation of a comb showing the sheath or casing in section, and

Fig. 3 is a cross-section on the line 3—3 of Fig. 2.

By reference to Fig. 2 of the drawing, it 40 will be observed that the comb includes the spine 1 from which the teeth 2 project. The spine 1 includes the enlarged end teeth 3 which form supporting members for a portion of the comb cleaning device about to 45 be described.

The cleaning device consists of a body 4 having a plurality of grids 5 which are adapted to enter the spaces between the comb teeth 2. As will be observed in Fig. 2, 50 one of the grids 5 occupies each space between the teeth 2 so that when the device 4 is removed in a manner and for purposes more fully to be explained, all accumulations of foreign matter upon the teeth 2 55 will be removed.

The sheath 4 includes side members 6 which are hinged as at 7 and include curved upper portions 8 which are adapted to snugly lie upon the upper edge of the spine 1 of the comb.

The hinged side members of the sheath 4 are secured together by a spring snap 9 which as will be seen in Fig. 3, is secured upon one of the side members and is adapted to engage the coöperating side member in 65 any suitable manner.

End sheaths 10 shaped to conform to the configurations of the ends 3 of the comb 1, are fitted over these teeth as shown in the drawing, and serve, in addition to acting 70 as supporting members, to preserve the smooth and unbroken configuration of the comb as will be clearly evident from an inspection of Fig. 1. It will be obvious that were it not for the provision of the end 75 sheaths 10, that the line of demarcation where the sheath portion 4 is divided as at 11, edges would result which would not only be rough to the touch causing the hair of the user's head to be caught therein, but 80 would also form a lodgment for undesirable accumulations of dirt.

The operation and use of the device is as follows: The sheath 4 is first applied to a comb so that the grids 5 will enter the spaces 85 between the teeth 2 and lie at the base of the teeth where they join with the spine 1. The sheaths 10 are then drawn over the teeth 3 at the same time since they form an integral part of the sheath structure.

The hinged sides 6 of the comb are then moved upon their hinges 7 so that the curved portions 8 will lie upon the curved upper portion of the spine 1 when the spring clasp 9 is fastened as will be evident from the 95 drawing. With continued use the teeth 2 will of course become more or less filled with accumulations of foreign matter. The ordinary manner of cleaning the comb is hardly ever satisfactory because it cannot 100 be done with comparative ease not to speak of the invariable soiling of one's fingers and clothing. With the use of my device a clasp 9 is simply unfastened, the hinged members 6 swung outwardly and the grid body 5 is 105 moved downwardly when as above explained, the accumulations on the teeth 2 will be scraped off. The cleaning of the grid 5 will be a comparatively simple matter since it can be immersed in boiling water 110

to loosen the dirt thereon. The grid 5 being accessible will permit the ready brushing of the dirt therefrom.

It should also be observed that the sheath 5 including the grid members 5 is made of 4 resilient material which together with the 40 resilient nature of the teeth 2 will work together to secure the effective removal of the foreign matter from the teeth. It should 10 also be understood that while the construction and arrangement of device as illustrated in the drawing is that of a generally preferred form, obviously modifications and changes may be made therein without deviating from the spirit of the invention or 15 parting from the scope of the claims.

I claim:—

1. In a cleaning device, the combination 20 with a comb having teeth, a sheath having grids adapted to normally be disposed at the base of the teeth, hinged side portions on the grids, and a clasp for joining the hinged side members upon the comb.

2. In a cleaning device, the combination 25 with a comb having a spine and teeth, of a sheath having grids adapted to enter the spaces between the teeth and normally lie at the base of the teeth, side members hinged to the grids, end sheaths, and a clasp for 30 securing the hinged side members about the spine of the comb.

3. In a cleaning device, the combination 35 with a comb having a spine and teeth, a sheath including end sheath members for engaging the end teeth of the comb, grids adapted to enter the spaces between the teeth and normally lie at the basis thereof, side members hinged at opposite sides of the sheath including curved portions for

engaging the upper edge of the spine, and a 40 spring on one of the side members adapted to engage the other for holding the sheath in position upon the comb.

4. In a cleaning device, the combination 45 with a comb having a spine and teeth, of a sheath having grids adapted to enter the spaces between the teeth and normally lie at the base of the teeth, side members hinged to said grids, end sheaths, and means for releasably retaining said side members in 50 set positions.

5. In a cleaning device, the combination 55 with a comb having a spine and teeth, a sheath including end sheath members for engaging the end teeth of the comb, grids 60 adapted to enter the spaces between the teeth and normally lie at the bases thereof, side members hinged at opposite sides of the sheath including curved portions for engaging the upper edge of the spine, and 65 means for holding said spine members in set positions.

6. In a cleaning device, the combination 65 with a comb having teeth, a sheath having grids adapted to normally be disposed of 70 the base of the teeth, hinged side portions on the grids, means releasably retaining said side members in set positions whereby when said side members are released they may be swung outwardly so as to entirely remove said grids from engagement with the teeth, for cleaning the comb.

In testimony whereof I affix my signature in presence of two witnesses.

PHILIP JOHNSTON.
